C. W. Hubbard,

Grinding Saws.

N° 79,980.

Patented July 14, 1868.

United States Patent Office.

CHARLES W. HUBBARD, OF PITTSBURG, PENNSYLVANIA.

Letters Patent No. 79,980, dated July 14, 1868.

IMPROVEMENT IN MACHINES FOR GRINDING SAWS.

The Schedule referred to in these Letters Patent and making part of the same.

TO ALL WHOM IT MAY CONCERN:

Be it known that I, CHARLES W. HUBBARD, of Pittsburg, in the county of Allegheny, and State of Pennsylvania, have invented a new and useful Improvement in Machines for Grinding Saws; and I do hereby declare that the following is a full and exact description thereof, reference being had to the accompanying drawings, and to the letters and figures of reference marked thereon.

The nature of my invention consists in providing machines for grinding saws with a metallic belt, which, in connection with feed-rollers, will move the saw-blade up to the action of the grindstone with a force only equal to the grinding-capacity of the grindstone.

My invention also consists in pivoting the bearing-roller of said machine, so that said roller and that part of the metallic belt which travels over it can be deflected with relation to the grinding-surface of the grindstone equal to the bevel desired in the saw-blade.

My invention also consists in providing the axis of grindstones with a flange which can be adjusted to any inclination of the sides of the grindstones.

To enable others skilled in the art to make and use my invention, I will proceed to describe its construction and operation.

In the accompanying drawings, which form part of my specification—

Figure 1 is a side elevation of my improvement in machines for grinding saws.

Figure 2 is an end elevation of the same.

Figure 3 represents a transverse section of the frame of the grinding-machine, cut through at line *y'*, with all the different parts of the machinery removed, except the bearing-roller *A'* and its bearings and operating-gear.

Figure 4 represents a transverse section of the grindstone and a longitudinal section of its shaft; also shows the socket-flange and its clamping-nut.

In the drawings, *A* represents the frame of the machine. Upon this frame are placed cast-iron pedestals, marked *B'*, in which are made the bearings for the shaft 16 of the drum *D*, and on which rest the bearings *J* for the shaft 18 of the drum *B*, also the bearings *l* of the feed-rollers 1 and 2, and to which are secured the columns *D'*, upon which move the bearings *X'* for the shaft *O* of the grindstone *C*. The shaft *O* is held in its bearings by means of caps 20 and set-screws *n*. The bearings *X'* are moved up and down on the column *D'* by means of screws *f*, which are made operative through the medium of the wheels 7, 8, 9, and 6. On the shafts *O* and 16 are placed pulleys *P* and *P'*, around which is placed a cross-belt, *R*. The roller *A'* has its bearings at *S* in the arms 17 of the piece marked *g*, which is pivoted at 14 to the arm marked *u*, which is attached to the end of the lever *w*, which is pivoted in the piece marked 12. The lever *w* is held in the desired position by means of the notches 1, 2, and 3 in the piece marked *X*. The piece *g* is provided with trunnions 13, which have their bearings in the supports marked *V*.

The metallic belt or endless apron marked *e* passes between the feed-rollers 1 and 2, and over the upper side of the bearing-roller *A'*, and around the drums *B* and *D*. The tension of the metallic belt or endless apron *e* is regulated by means of the set-screw, *K*, through the medium of which the bearings *J* of the axle 18 of the drum *B* may be moved back or forward, and thereby obtain the desired distension of the metallic belt or apron *e*. The sides of the grindstone *C* are very often inclined, or thicker at one side than at the other, (when viewed in cross-section,) as clearly indicated by the line *y* in fig. 4. To overcome this difficulty the opening in the flange *i*, through which the axle *O* passes, is made greater than the diameter of the axle, and in the outer face of the flange *i* and screw-nut *Z* (clearly shown in fig. 4) the grindstone can be secured firmly on the shaft *O*, without subjecting the shaft to undue strain, which is always the case when the sides of the grindstone are inclined and the flanges are forced up against the side of the grindstone in the ordinary manner.

As the construction and arrangement of the several parts of my improvement in machines for grinding saws will be readily seen and understood by the skilful mechanic by reference to the accompanying drawings,

I will therefore, without further description of its construction, proceed to describe its operation, which is as follows:

All things being arranged as herein described and represented, motion is imparted to the pulley P' , which will revolve the grindstone C . From the pulley P' to pulley P , motion is transmitted through the medium of the cross-belt R , which motion should be so arranged with relation to other pulleys or gear as to impart to the drums B and D , feed-rollers 1 and 2, and bearing-roller A' and metallic belt or endless apron e , an alternate or reciprocating motion. The tension of the feed-rollers 1 and 2 upon the metallic belt e being adjusted through the medium of the set-screws m , the saw-blade to be ground is placed upon the metallic belt e , which will carry it under the feed-roller I , and the combined action of the metallic belt and feed-rollers 1 and 2 will carry the saw back and forward under the grindstone C , which is brought in contact with the saw-blade by turning the wheel h , which will turn wheels 6 and 8, which will turn wheels 7 and 9, which will turn the screws f , which will lower the bearings X' of the shaft O , and thereby bring the grindstone C in contact with the saw-blade. The bearing-roller A' will hold up the metallic belt e , and thereby keep the saw-blade in contact with the grindstone. The desired bevel is given to the saw-blade by deflecting the bearing-roller A' from its horizontal plane, as indicated by the dotted lines marked 10, (see fig. 3.) This deflection of the roller A' is accomplished by moving the lower end of the piece g , as indicated by the dotted lines marked 11, which is done through the medium of the arm u and lever w , which can be held in the desired position by means of the notches 1, 2, and 3, in the piece X .

The advantage of feeding the saw-blade up to the action of the grindstone through the medium of the metallic belt, combined with the action of the feed-rollers 1 and 2, is that the belt will only feed the saw up to the grindstone in proportion to its grinding-power; that is to say, the belt will slip or yield back on the drums B and D , so that the saw will not be carried under the grindstone faster than it is cut or ground off on a given plane. By thus feeding the saw up to the grindstone with that speed and force which are just equal to its grinding-capacity, the result will be the production of a saw-blade having a smooth and even surface—a result which cannot be obtained with a feed-device, the action of which is positive and unyielding.

The advantage of deflecting the bearing-roller A' from its horizontal plane is, that through the medium of such deflection, any desired bevel of the saw-blade may be obtained, which bevel will in every case be uniform, the advantage of which will be apparent to every mechanic skilled in the art of grinding or using saws.

Having thus described the nature, construction, and operation of my improvement, what I claim as of my invention, is—

1. Providing a saw-grinding machine with an unjointed thin metallic belt or endless apron, substantially as herein described and for the purpose set forth.
2. Pivoting the bearing-roller A' so that it can be deflected to correspond to the desired taper of the saw-blade, substantially as herein described and for the purpose set forth.
3. Providing the shaft of a grindstone with a flange provided with a socket-joint, substantially as herein described and for the purpose set forth.

C. W. HUBBARD.
